UNITED STATES PATENT OFFICE.

LE GRAND SKINNER, OF ERIE, PENNSYLVANIA, ASSIGNOR, BY MESNE ASSIGNMENTS, TO THE SKINNER ENGINE COMPANY, OF SAME PLACE.

ENGINE-FRAME JIG.

SPECIFICATION forming part of Letters Patent No. 349,757, dated September 28, 1886.

Application filed June 4, 1885. Serial No. 167,662. (No model.)

To all whom it may concern:

Be it known that I, LE GRAND SKINNER, a citizen of the United States, residing at Erie, in the county of Erie and State of Pennsylvania, have invented certain new and useful Improvements in Engine-Frame Templets or Jigs; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to improvements in engine-frame templets; and it consists in the mechanism hereinafter set forth and explained in the specification and claims.

20 My invention is illustrated in the accompanying drawings, in which Figure 1 is a perspective view of my improved engine-frame templet or jig with parts thereof detached. Fig. 2 is a perspective of the cylinder-head face-plate thereof. Fig. 3 is a perspective view of the detachable rocker-shaft templet mechanism thereof. Fig. 4 shows a collar to be placed in front of cylinder-plate. Figs. 5 and 6 show details.

25 Similar letters refer to like parts in all the figures.

In the construction of my improved templet or jig, B is the main supporting rod or frame thereof. Firmly secured to one end of the rod B is a cross-piece, A A, adapted to be placed in the pillow-block boxes of an engine. This cross-piece A A is provided with fixed collars a a, and also with loose collars a' a', adapted to fit against the inner and outer ends of the pillow-block boxes, so that molten babbitt 35 may be poured into the boxes over the cross-pieces A A for fitting the same for the shaft. Securely attached to the central part of the rod B are also blocks or bearings G G, provided with holes g g, adapted to receive, line up, and 40 sustain the guide-bolts while the same are being babbitted into place in an engine-frame. Clamped to the rod B between the blocks G G is also an arm, H, which is kept from turning on the rod B by the fin h'. The lower end of 45 the arm H is provided with a cross-sleeve, H', and set-screw h, this sleeve H' being adapted

to receive and support the rocker-shaft templet-rod H², for lining up and babbetting the rocker-shaft boxes on an engine-frame.

On the end of the rod B, opposite the pillow-block cross-piece A A, I place a recessed collar, E, (shown as detached in Fig. 1,) and also a sleeve, D, this sleeve D being adapted to pass through the opening in the cylinder-head on an engine-frame to and against a cylinder-head face-plate, C, hereinafter referred to. The end of the collar E is provided with a set-screw, e, and is adapted to slip on the end of the collar D and leave some space between a portion of said sleeve D and the outer end of the collar E, so that the collar E is adapted to fit over the end of the sleeve D and against the end of the cylinder-head, where it is secured in place by the set-screw e operating against the supporting-rod B.

25 On the outer end of the supporting-rod B, I place a face-plate, C, which is provided with a long sleeve, C', adapted to fit the rod B closely and slide thereon. The face of the plate C is adapted to be shoved up adjacent to the face of the cylinder-head and against the end of the sleeve D, substantially as shown in Fig. 1, when it may be secured by a set-screw (not shown) upon the supporting-rod B. Holes c are also provided in the face-plate C, 30 into which templet-pins c' may be placed, which will pass through openings for the bolt-holes in the cylinder-head; these templet-pins c' being provided with sliding collars c'', adapted to fit against the outer end of the cylinder-head, and having set-screws therein for securing them in place; this face-plate mechanism being so arranged that when in place on an engine-frame molten babbitt or other metal may be poured between the same 35 and said cylinder-head, and the same thereby turned up in line with other bearings on the engine-frame, and thereby finished ready for the reception of a cylinder and stuffing-box.

40 In the drawings I have shown a simple and convenient form of templet or jig for the purpose specified. However, I do not desire to limit myself to the peculiar form of construction shown, as it is obvious to those skilled in the art to which it appertains that it can 45 readily be constructed in many different shapes and good results obtained therewith without

in any wise departing from the spirit of my invention.

Having thus fully described my improvement and the adaptation of its several parts, 5 its operation will be obvious to those conversant with the art to which it appertains without further description thereof; therefore,

What I claim as new, and desire to secure by Letters Patent of the United States, is—

10 1. In a templet or jig, a cross-bar adapted to rest in the pillow-block boxes of an engine-frame, provided with and having attached thereto a rigid rod or frame extending to or beyond the cylinder-head on such engine-frame, in combination with a movable face-plate adapted to cover the face of such cylinder-head, and to be adjusted thereto on said rod or frame so as to line up with the pillow-block boxes, substantially as and for the purpose set forth.

15 2. The combination, in a templet or jig, of a cross-bar adapted to rest in the pillow-block boxes of an engine-frame, and a rigid rod or frame attached thereto and extending to the cylinder-head on such engine-frame, with 25 bearings or supports on said rod or frame, to which the guide-bolts may be adjusted and lined up with the pillow-block boxes and the cylinder-head on an engine-frame, substantially as and for the purpose set forth.

30 3. The combination, in a templet or jig, of

a supporting-rod provided with a cross-piece adapted to fit the pillow-block boxes of an engine-frame, with a face-plate adapted to cover the face of a cylinder-head on said frame, 35 templet-pins adapted to pass through cylinder bolt-hole openings, and a collar and sleeve adapted to pass through the stuffing-box in such cylinder-head, substantially as and for the purpose set forth.

40 4. The combination, in a templet or jig, of a supporting-rod provided with a cross-piece adapted to be placed in the pillow-block boxes of an engine-frame, and with an adjustable cylinder-head face-plate adapted to cover the 45 face of the cylinder-head on such engine-frame, with bearings or supports attached to said rod for adjusting and sustaining guide-bolts, substantially as and for the purpose set forth.

45 5. The combination, in a templet or jig, of a supporting-rod provided with a pillow-block templet-rod, an adjustable cylinder-head face-plate, and guide-bolt supports, with an arm on said rod supporting a rocker-shaft templet-rod, substantially as and for the purpose set forth.

In testimony whereof I affix my signature in presence of two witnesses.

LE GRAND SKINNER.
